UNITED STATES PATENT OFFICE

161,806

LAWN SPRINKLER

William C. Wehner, Grosse Pointe Park, Mich.,
assignor to Wehner Engineering Company,
Grosse Pointe Park, Mich., a corporation of
Michigan

Application August 17, 1950, Serial No. 11,817

Term of patent 14 years

(Cl. D91—1)

To all whom it may concern:

Be it known that I, William C. Wehner, a citizen of the United States of America, a resident of the city of Grosse Pointe Park, in the county of Wayne, State of Michigan, have invented a new, original, and ornamental Design for a Lawn Sprinkler, of which the following is a specification, reference being had to the accompanying drawing, forming part thereof.

Figure 1 is a top plan view of a lawn sprinkler, embodying my new design;

Figure 2 is a side elevation;

Figure 3 is a front elevation;

Figure 4 is a perspective from the same side as Figure 2; and

Figure 5 is a rear elevation with the dome in tilted position.

I claim:

The ornamental design for a lawn sprinkler, as shown.

WILLIAM C. WEHNER.
